CLAIM

The ornamental design for a golf ball marker holder, as shown and described.

DESCRIPTION

FIG. 1 is a perspective view of a golf ball marker holder according to the present design.

FIG. 2 is a first side view of a golf ball marker holder according to the present design.

FIG. 3 is a second side view of a golf ball marker holder according to the present design.

FIG. 4 is a third side view of a golf ball marker holder according to the present design.

FIG. 5 is a fourth side view of a golf ball marker holder according to the present design.

FIG. 6 is a top view of a golf ball marker holder according to the present design; and,

FIG. 7 is a fourth side view of a golf ball marker holder according to the present design.

The broken lines in the figures illustrate portions of the golf ball marker holder that form no part of the claimed design.

1 Claim, 6 Drawing Sheets
